Fig. 2

Fig. 4

Fig. 3

FIGURE 1 is a side view of a rivet gun or similar fastening tool showing my new design;

FIGURE 2 is a top view of the tool in FIGURE 1;

FIGURE 3 is a rear view of the tool in FIGURE 1;

FIGURE 4 is a front view of the tool in FIGURE 1. The dominant features of my design reside in the portions shown in full lines.

I claim:

The ornamental design for a rivet gun or similar fastening tool, substantially as shown and described.
